UNITED STATES PATENT OFFICE

FERDINAND S. BARBIERS, OF LANCASTER, OHIO, ASSIGNOR TO THE HOCKING GLASS COMPANY, OF LANCASTER, OHIO, A CORPORATION OF OHIO

DESIGN FOR A TUMBLER

Application filed January 21, 1932. Serial No. 42,577. Term of patent 7 years.

To all whom it may concern:

Be it known that I, FERDINAND S. BARBIERS, a subject of the King of Belgium, residing at Lancaster, in the county of Fairfield and State of Ohio, have invented a new, original, and ornamental Design for a Tumbler, of which the following is a specification, reference being had to the accompanying drawing, forming part hereof.

In the drawing, which illustrates one form that my design may take, the figure represents a perspective view of a tumbler embodying my new design.

The dominant features of the design reside in the stepped drop between the rows of diamond-shaped surfaces with the arrangement of such surfaces in staggered relationship, so that an accentuated fish scale effect is obtained.

I claim:

The ornamental design for a tumbler, substantially as shown and described.

FERDINAND S. BARBIERS.
